STEREOPHONIC AMPLIFIERS AND OUTPUT TRANSFORMERS

Norman H. Crowhurst, Bayside, N.Y., assignor to Columbia Broadcasting System, Inc., New York, N.Y., a corporation of New York

Filed Nov. 9, 1960, Ser. No. 68,206

20 Claims. (Cl. 179—1)

The present invention relates to stereophonic amplifiers and output transformers.

In the realistic reproduction of sound it has become a matter of recognized importance to create the stereophonic effect by providing two or more speakers that are spaced apart in front of the listener. Each speaker is supplied with audio signals from stereophonic recordings or from microphones judiciously placed in relation to the sources of sounds so as to preserve the sense of direction identified originally with each of the sounds to be reproduced. Elaborate systems have been used for this purpose, including two completely separate stereo channels, each having its own amplifier and speaker. For desirable standards of fidelity, each channel has included separate speakers for the high and low frequency ranges, and each channel has included its own frequency-separation network for selective coupling to such speakers.

Duplicate stereo channels represent duplications of expensive components. It has heretofore been proposed that the relatively narrow range of low-frequency signals can be reproduced by a common low-frequency speaker. The three-dimensional stereophonic effect is largely preserved by means of separated satellite speakers energized only by the "highs" from separate stereo amplifying channels. This proposal, while representing an important economy, nevertheless involves a considerable amount of expense that is proved unnecessary by the present invention.

An object of the present invention is to provide novel coupling means in a stereo amplifier that is economical yet highly effective for accomplishing the combined purposes of separating "highs" and "lows" in the signals from separate stereo channels, of maintaining stereo separation between the "highs" from the two channels, and of providing common low-frequency output from both channels for a common low-frequency speaker. A further object of the invention resides in novel coupling means wherein all these purposes are carried out compatibly, without any serious disturbing interaction. A further object is to provide novel coupling means for the combined functions mentioned, wherein the coupling means is of minimized complexity, of correspondingly greater reliability, and of lower cost than comparable circuit networks heretofore used.

Three illustrative embodiments of the invention for accomplishing the foregoing objects are described in detail below. Each utilizes a coupling unit consisting of a novel transformer, and a capacitor. The coupling unit separates the "highs" of each stereo channel from the "lows" and it achieves a high degree of stereo separation between the "highs," and it further provides output connections for supplying the combined "lows" of both channels to the common low-frequency speaker.

In each of these embodiments, the transformer includes three speaker-energizing windings separated from each other, but linked by a common magnetic core. The transformer in two of the embodiments includes two primary windings that are tightly coupled to respective secondary windings, and both of these windings are loosely coupled to a third winding. In the third embodiment of the invention, no impedance transformation is needed, and the primary windings are omitted. There are three windings on a common core in all three embodiments, the third

2

winding being loosely coupled to the other two. As a convenient generic term, the core and winding assemblies in all of the embodiments are herein termed "transformers."

5 The third winding of the transformer in each form described is shunted by a capacitor whose size is dependent upon the other circuit impedances and upon the desired crossover frequency, to separate the "highs" from the "lows." This winding energizes the common low-frequency speaker in each of the forms to be described.

The two stereo windings, while on the same magnetic core as that of the third winding, are separated from each other sufficiently to promote high-frequency isolation between the stereo channels. The use of a single transformer in each coupling unit, with its common-core linking both stereo windings to the common third winding, represents important advantages. It involves a minimum number of parts, and of assembly costs; and it assures a high degree of symmetry in the coupling between the 15 channels and the speakers without critical selection of components such as would be entailed if separate circuit networks were used. Further, it maintains a high level of isolation between the stereo signals without critical dependence on the character of the load (whether markedly resistive or inductive) connected to the coupling unit.

Each stereo channel can utilize a pair of push-pull amplifier tubes or transistors at the output end, as will appear. However, it has been found that the novel transformer operates within reasonable limits of distortion even 30 where each channel has only a single-sided output, that is, where each channel uses only one tube or transistor in its output stage. This is in part attributable to the fact that the direct currents supplied to the amplifying devices through the corresponding transformer windings are polarized so as to set up mutually opposing magnetic fields in the magnetic core loop (thus avoiding saturation), and it is in part attributable to the fact that the low-frequency components of stereo input are oppositely phased relative to each other in the two stereo channels 35 and behave in the novel stereo output transformer approximately in the same manner as push-pull signals conventionally supplied to the primaries of an ordinary push-pull output transformer. It is legitimate to consider the low-frequency audio signals as oppositely phased, since these "lows" are inevitably picked up originally in this phase relationship, and in a reasonably symmetrical pair of stereo channels the phase opposition is preserved. Moreover, it is usual for both of the stereo channels to carry a prominent component of monophonic information. This 40 factor contributes to the success of the novel coupling unit, but is not essential to its satisfactory operation.

For minimizing distortion, particularly where single-sided output stages are used in the stereo channels, and to enhance stereo separation between the "highs," negative feedback connections in the stereo amplifying channels are highly desirable. For this purpose, a reference connection is made to the midpoint of the common low-frequency output winding in two of the disclosed transformers. If this were done with a simple center-tap in an 45 ordinary winding for the common "lows," other distortion components might well develop such as frequency-doubling and high-frequency resonances. These difficulties are connected with high-frequency stereo performance, but they arise in the low frequency common coupling circuit. Those distortion effects have been avoided, pursuant to an important specific feature of the invention, by utilizing a bifilar winding in the low-frequency common output circuit. The halves of such winding are 50 extremely closely coupled and eliminate any troublesome leakage reactances at this point. Any such leakage reactances, with capacitances that exist between windings, tend to introduce objectionable resonances.

The parts of the bifilar winding are connected to each other so as to afford a common ground, simplifying connection of separate feed-back circuits in the two stereo channels. Negative feedback of the full-range signal of each channel may be used for minimizing distortion. However, the available frequency selective output points can be used in negative feedback loops for bass and treble gain control which thus further improves fidelity. The tight-coupled halves of the bifilar winding with their common connection as a reference point makes this effective without introducing spurious effects in the main functions of the transformer, and it simplifies the connections of the feedback loops to the transformer.

Accordingly, an additional object of the invention resides in the construction of transformers that are especially suited to use in stereo systems of the class described.

The nature of the invention will be more fully appreciated and further objects and novel features will be apparent from the following detailed description of various embodiments shown in the accompanying drawings. In those drawings:

FIG. 1 is a wiring diagram of a presently preferred embodiment of the invention;

FIG. 2 is a somewhat enlarged cross-section of the transformer in FIG. 1, together with certain of the circuit connections of FIG. 1, shown diagrammatically; and

FIGS. 3 and 4 are wiring diagrams of modifications.

Two stereo channels are shown in FIG. 1, a "right" channel 10 and a "left" channel 12, having stereo input at points 14 and 16. A full range of audio-frequency signals are supplied at these input terminals by stereo pre-amplifiers (if needed) and these are ordinarily energized by stereo pickups from a recording. Stereo signal input might alternatively come from microphones suitably arranged relative to the sound sources.

Inasmuch as channels 10 and 12 are identical, only the components of channel 10 are specifically described, the corresponding components in channel 12 being identified by corresponding primed numbers. Signal from input terminal 14 is supplied to triode amplifier 18 by gain-control potentiometer 20 via coupling capacitor 22. Amplifier 18 has a grid-return resistor 24, a plate load resistor 26, and a self-bias resistor 28. Triodes 18 and 18' are sections of a dual triode.

Signal from the anode of amplifier 18 is coupled to output pentode 30 by coupling capacitor 32. Output pentodes 30 and 30' have a common self-bias resistor 34 and bypass capacitor 36. Each of these pentodes serves as a single-sided output amplifier in its channel. A common output transformer 38 provides output coupling from both pentodes 30 and 30' to two high-frequency speakers 31 and 31' and to a common low-frequency speaker 33.

A primary winding 40 serves as the anode load of pentode 30, and primary winding 40' similarly is the load of pentode 30'. Secondary windings 42 and 42' are tightly coupled to primary windings 40 and 40', respectively. An additional secondary winding including parts 44 and 44' is spaced from both primary and secondary windings 40-42 and 40'-42'. Consequently, there is only loose coupling from the primary and secondary windings to the additional secondary 44, 44'. Parts 44 and 44' are the halves of a bifilar winding, the start of one half being connected to the finish of the other half.

All of the windings 40, 40', 42, 42', 44 and 44' are disposed on a common core 46, that provides a closed magnetic loop through all of these windings (FIG. 2). Windings 40 and 42 are relatively remote from windings 40' and 42', and are thus loosely coupled to each other so as to have a minimum of high-frequency coupling.

Winding 40 carries the D.-C. plate current of output pentode 30 from D.-C. terminal 47, and winding 40' similarly carries the D.-C. plate current of amplifier 18 from terminal 47. These windings are disposed opposite each other on core-loop 46, the connections being

polarized so that there is normally no D.-C. magnetization in the core.

A capacitor 48 is connected across the opposite terminals of bifilar winding 44-44'. Windings 42 and 44 have an equal number of turns and are connected by a lead 50 so that these windings are in series-opposition. Consequently output terminals 52 and 54 (which are also the remaining terminals of windings 42 and 44) provide no low-frequency output.

The high-frequency components of the signal in primary winding 40, which is tightly coupled to secondary winding 42, are obviously available at terminals 52 and 56. Because of the leakage reactance resulting from the loose couplings between windings 40 and 44, there is very little of the high-frequency signal coupled to the winding 44; and by virtue of the tight coupling between halves 44 and 44' of the bifilar winding and because of the capacitor 48 which shunts these series-connected bifilar winding portions, winding 44 does not interfere with the efficient transmission of the high-frequency signals of channel 10 from terminal 56 to terminal 54. Consequently high-frequency signals from channel 10 reach terminals 52 and 54, to energize "left" high-frequency speaker 31. By like token, high-frequency signals from channel 10' reach terminals 52' and 54' to energize "right" high-frequency speaker 31'.

Low-frequency signals in channels 10 and 12 are opposite in phase, with proper stereo input connections to the two channels. With the relative sense of windings 40 and 40' described above (for D.-C. magnetic field neutralization) the low-frequency signals thus simulate push-pull signals in windings 40 and 40'. Low-frequency signals are efficiently coupled via bifilar winding 44-44' to terminals 54 and 54', for energizing common low-frequency speaker 33.

Channels 10 and 12, and output coupling transformer 38 are thus seen to be effective for providing two high-frequency stereo signals separately at terminals 52-54 and at terminals 52'-54', respectively, for a pair of satellite high-frequency speakers and, independently, a common, combined low-frequency signal is available from channels 10 and 12 at terminals 54 and 54' for a common low-frequency speaker 33. The cross-over frequency between the high and low-frequency signals may, for example, be 250 cycles per second. Above this cross-over frequency, the transformer described, together with by-pass capacitor 48, provides excellent stereo-signal separation so that the stereo signal in channel 10 appears at terminals 52 and 54 with only a minimal signal from channel 10' appearing at terminals 52' and 54'. Similarly, the high-frequency signal in stereo channel 12 is coupled to output terminals 52' and 54', with only a minimal portion of this signal appearing at terminals 52 and 54. Below the cross-over frequency, the low-frequency components of the stereo signals in channels 10 and 12 are combined, and the combined signal is available at terminals 54 and 54' for the common low-frequency speaker 33.

The circuit arrangement and output coupling means described involve leakage reactances between primary windings 40 and 40' and secondary winding 44-44'. By virtue of any other reactances and the inherent capacitances present in the transformer, difficulties might develop in the form of objectionable resonances and generation of second-harmonic frequencies in the high-frequency range. Indeed, such difficulties might well develop with the circuit illustrated in the absence of very close coupling between winding portions 44 and 44'. The bifilar winding arrangement of winding 44-44' is an effective way to avoid such distortion while, at the same time, providing a common reference point 56 that is important to the feedback connections detailed below.

Terminal 56, which is the junction between portions 44 and 44' of the bifilar secondary winding, provides a reference point for separate negative feed-back signals for the two stereo channels. Negative feed-back contrib-

utes materially to the present amplifier. Each primary winding 40 and 40' might be energized by a pair of output amplifier tubes arranged in push-pull (see FIG. 4); but this represents an added cost. The single-sided output stages 30 and 30' have been found quite satisfactory from the point of view of limited distortion, particularly at moderate power-output. This fidelity is enhanced through negative feed-back loops. The negative feed-back also enhances stereo separation. Negative feed-back signal is coupled to the cathode of amplifier 18 by resistor 58 and capacitor 60. Frequency-selective negative feed-back is also furnished, this being adjustable for bass and treble control. Capacitor 62 and resistor 64 provide an output point at which an adjustable treble control 66 is connected. Resistor 68 limits the maximum feed-back of high-frequency signal to the negative feed-back point at the cathode of amplifier 18. Negative feed-back of low-frequency signals is adjustably controlled by variable resistor 70 which is connected between terminal 54 and the cathode of amplifier 18, series resistor 72 limiting the maximum amount of negative feed-back of low-frequency signals. Resistors 28 and 76 and capacitor 78 constitute the load to which the negative feed-back signals are applied, resistor 76 being much smaller than resistor 28 in a practical embodiment. Treble-control variable resistors 66 and 66' are mechanically coupled to each other for conjoint operation, as are bass-control variable resistors 70 and 70'.

It would be possible to omit parts 60, 62, 64, 66, 68, 70, 72, 76 and 78 and their primed counterparts and nevertheless retain full-range negative feedback through resistors 58 and 58' to resistors 28 and 28'. However, the preferred embodiment of the invention demonstrates not only the unique performance of the output transformer in the circuit illustrated, as an output coupling device, but this embodiment also demonstrates the additional advantage of improved bass control that is realized through adjustable negative feedback from the low-frequency output portions of the novel transformer. Negative feedback is separately effected of the treble components of the stereo signals, as described, for improved fidelity and stereo separation, and for treble gain control.

The actual structure of transformer 38 is represented in FIG. 2, together with the input, output and feed-back connections of the circuit in FIG. 1. In FIG. 2, the magnetic core 46 includes stacked U-shaped core laminations 46a and I-shaped core laminations 46b. These laminations are advantageously of non-oriented silicon steel. The legs of U-shaped lamination 46a are seen to be unequal. The long-leg sides 46c alternate with short legs 46d of other stacked U-shaped laminations. By like token, it is seen that I-shaped lamination 46b projects across the end of the shorter leg 46d; and this projection extends in opposite directions from each lamination to the next in the stack of laminations, to abut the successive short legs 46d of the U-shaped laminations.

Winding 40 of FIG. 1 is seen in FIG. 2 to be divided into two portions 40a and 40b, respectively outside and inside secondary winding 42, to enhance the desired tight coupling. Correspondingly, winding 40' is divided into two portions, 40a' and 40b', outside and inside secondary winding 42' on the other leg of the U-shaped portion of the core. As illustrated, the starts of windings 40b and 40b' extend to the anodes of amplifier tubes 30 and 30'. The opposite ends of the primary windings extend to B-plus as illustrated. One end of each of the secondary windings 42 extends to ground, and the other ends of these secondaries extend to the output point 52 and 52', so phased as to provide negative feed-back for its own amplifier channel.

The illustrated division of primary windings 40 and 40' each into two parts is one way of obtaining tight coupling between primaries and secondaries. However, other winding arrangements will be found effective. One practical arrangement is to dispose each entire primary wind-

ing, undivided, under its corresponding secondary. Other suitable winding arrangements may be substituted.

Bifilar winding 44, 44' is disposed on the I-shaped core laminations 46b, the start and finish of alternate bifilar winding portions forming the grounded terminal 56. From the phasing determined by the connections to windings 42 and 42' (in providing negative feed-back) the remaining connections of the bifilar winding are brought out as second connections for the "left" and the "right" high-frequency speakers 31 and 31', phased so that the output from the two windings 42 and 44 will cancel below 250 cycles. (This is determined more readily without capacitor 48 connected.)

It is seen that transformer 38 and capacitor 48 provide the entire output coupling means from the stereo channels 10 and 12 to the three speakers including satellite speakers 31 and 31' and common bass speaker 33. Stereo separation between the "highs" is preserved, and frequency division between the stereo-separated "highs" and the common "lows" are all achieved by the single transformer 38 and capacitor 48. Symmetry between the two channels is realized without exacting care in matching separate inductors or other components found in coupling networks used previously. A common reference point is made available for negative feed-back circuits, and frequency-selective feed-back points are likewise available for bass and treble gain control. Single-sided output stages in the stereo channels are accommodated. The stereo separation is achieved without critical dependence on the character of the load impedance, whether inductive or resistive.

A modification of the circuit in FIGS. 1 and 2 is illustrated in FIG. 3, in which 100-series numbers are employed to designate parts corresponding to those in FIGS. 1 and 2. In FIG. 3, the stereo channels 110 and 112 employ transistors, or speakers having high impedance matching other amplifiers are used, so that the output circuit can be coupled directly to the speakers, without impedance transformation. For this reason, in FIG. 3 the primary windings of the transformer 38 in FIGS. 1 and 2 do not appear in FIG. 3. Windings 142 and 142', disposed on the opposite legs of U-shaped magnetic core laminations, are connected directly to the amplifying devices in channels 110 and 112, so as to carry the energizing direct-current of those devices. Bifilar windings 144-144' is similarly mounted on the end portion of the core, shunted by capacitor 148. The various windings are connected to each other in FIG. 3 and phased in relation to each other as in FIGS. 1 and 2, the significant difference being that the close-coupled primary windings of FIGS. 1 and 2 are omitted. Like feed-back connections are provided, and like speaker connections are included. D.-C. blocking and high-frequency coupling capacitors 157 and 157' are interposed between transformer windings 142 and 142' and the respective high-frequency speakers 131 and 131'.

Windings 142 and 144 are loosely coupled. The resulting leakage inductance limits high-frequency signal coupling from winding 142 to 144. These windings have an equal number of turns and are connected in series-opposition.

Capacitor 148 complements the transformer in establishing the cross-over frequency. Little if any low-frequency output appears at speakers 131 and 131'. Direct current supply 159 may, for example, be interposed between the common connection of winding portions 144 and 144' and ground, for providing direct current for output transistors or other amplifiers in channels 110 and 112. Suitable feed-back connections from terminals 152, 152', 154 and 154' of the transformer are to extend to the respective amplifier channels 110 and 112, and may include frequency-selective components as in the circuit of FIG. 1.

There is distinct economy to be realized without introducing notable distortion through use of single-sided

amplifiers at the output ends of channels 10 and 12. This is particularly true when it is considered that there is a substantial monophonic push-pull component in usual stereophonic signals. However, it is entirely feasible for push-pull amplifiers to be used in the output. Such an arrangement is illustrated in FIG. 4. In this embodiment, the primary windings 240 and 240' are center-tapped and the center-taps are connected to B-plus. Dual-section output amplifiers 230 and 230' are connected to the opposite ends of primary windings 240 and 240'. A simple winding 244 is used to provide common low-frequency signals for low-frequency speaker 233. Just as in FIGS. 1 and 2, windings 242 and 244 are connected in series-opposition to high-frequency speaker 231 for one of the channels, and windings 242' and 244 are connected in series-opposition for energizing the speaker 231' for the high-frequencies of the other channel. The phasing of the signals in the two channels is to be such in relation to windings 240 and 240' so that these primary windings complement each other in producing low-frequency signal output in winding 244.

Negative feed-back connections are not shown in FIG. 4, but such connections can be used if desired. Greater circuit complexity is entailed and hence the bifilar winding arrangement in FIGS. 1 and 2 and in FIG. 3 are preferred. Nevertheless, the circuit of FIG. 4 represents an embodiment of certain broader aspects of the invention.

The embodiments of FIGS. 3 and 4 achieve certain of the functions and economies of the embodiment in FIGS. 1 and 2, and all three, in common, include a single transformer having a core loop that couples a pair of stereo input windings loosely to a third winding that is shunted by a capacitor. In each case, the frequency separation of both stereo signals into "highs" and "lows" is accompanied by maintenance of stereo separation between the "highs" and by combination of the "lows" in a common output circuit. All three coupling arrangements are characterized by inherent symmetry and by minimal circuit complexity.

In all three embodiments the cross-over frequency is determined by the capacitor 48, 148 or 248 in conjunction with the leakage inductance between windings 42, 42' and 44, 44' relative to the connected circuit impedances. In a practical example of the form in FIGS. 1 and 2, transformer 38 had primaries of 3200 turns, secondaries of 110 turns each, a bifilar winding having 110 turns for each half, and the laminated core of non-oriented silicon steel had a cross-section of $\frac{3}{8}$ inch square. The impedance of the bifilar winding between terminals 54 and 54' was 8 ohms, and capacitor 48 was a 100 mfd. electrolytic unit.

In each of the circuits illustrated, there is a common low-frequency speaker and a pair of high-frequency stereo speakers. These circuits can be used to advantage even with full-range stereo speakers in place of the high- and low-frequency speakers shown in the drawings.

Full-range stereo signals may be obtained for such full-range stereo speakers from the circuits illustrated if this should be necessary. For example, a full-range speaker for channel 10 in FIG. 1 may be connected between terminals 52 and 54' and the full-range speaker for channel 12 may be connected between terminals 52' and 54.

For such full-range speaker operation, this invention offers a special advantage that will be clear from the following. It is characteristic of dynamic speakers that they have a considerable rise in impedance in the region of their low-frequency resonance. In normal amplifier design this results in mis-match and loss of available power at these frequencies. In the circuit of FIG. 1, by connecting a full-range speaker for channel 10 between terminals 52 and 54' and a full-range speaker for channel 12 between terminals 52' and 54, the impedance match changes at the crossover frequency. Above this point, the transformer matching suits the higher frequency voice coil impedance. Below it, the impedance match will rise to a higher value. Using equal turns in windings 42 and 42'

with those in each part of the bifilar section 44 and 44', the impedance rise will be a factor of 4 times. By using turns combinations other than equal, which will still be effective in preserving separation above the crossover frequency just as well, any impedance rise factor desired may be achieved, less or more than 4 times.

It is apparent that additional variations and varied applications of the novel features found in the embodiments described above will occur to those skilled in the art, and therefore it is appropriate that this invention should be broadly construed in accordance with its full spirit and scope.

What is claimed is:

1. A stereophonic amplifier having "right" and "left" amplifier channels, "right" and "left" high-frequency speakers and a common low-frequency speaker, and output coupling means between said channels and said speakers for dividing the output signals of said channels into high and low-frequency signals above and below a cross-over frequency, and for maintaining stereo separation between the high-frequency signals while providing combined output of low-frequency signals from both channels, said output coupling means including a transformer having a magnetic core, a common winding disposed on said core and connected to said low-frequency speaker, additional windings on said core connected at the output of said stereo channels respectively, said additional windings being relatively remote from each other and spaced symmetrically about said common winding, each of said additional windings being connected in series-opposition to said common winding in respective output circuits and each of said output circuits being connected to a respective one of said high-frequency speakers, and a capacitor connected across said common winding and relatively proportioned to determine the cross-over frequency.

2. A stereophonic amplifier having "right" and "left" amplifier channels, "right" and "left" high-frequency speakers and a common low-frequency speaker, and output coupling means between said channels and said speakers for dividing the output signals of said channels into high and low-frequency signals above and below a cross-over frequency, and for maintaining stereo separation between the high-frequency signals while providing combined output of low-frequency signals from both channels, said output coupling means including a transformer having a magnetic core, a common low-frequency winding disposed on said core and connected to said low-frequency speaker, primary windings on said core at the output of said stereo channels respectively, respective secondary windings on said core tightly coupled to said primary windings, each of said secondary windings being connected in series-opposition to said common winding in respective output circuits and each of said output circuits being connected to a respective one of said high-frequency speakers, and a capacitor shunting said common winding and relatively proportioned to determine the cross-over frequency, said primary windings being disposed relatively remote from each other and symmetrically about said common winding.

3. A stereophonic amplifier having "right" and "left" amplifier channels, corresponding "right" and "left" high-frequency speakers and a common low-frequency speaker, and output coupling means between said channels and said speakers for dividing the output signals of said channels into high and low-frequency signals above and below a cross-over frequency, and for maintaining stereo separation between the high-frequency signals while providing combined output of low-frequency signals from both channels, said output coupling means including a transformer having a magnetic core, a common bifilar winding having the start of one-half thereof joined to the finish of the other half thereof, said bifilar winding being connected to said low-frequency speaker, additional windings on said core at the output of said stereo channels respectively, said additional windings being relatively widely spaced from

each other and spaced symmetrically about said bifilar winding, each of said additional windings being connected in series-opposition to said bifilar winding in respective output circuits and each of said output circuits being connected to a respective one of said high-frequency speakers, a capacitor shunting said bifilar winding and relatively proportioned to determine the cross-over frequency, and negative feed-back connections from said windings to said channels and including the joint between the halves of said bifilar winding.

4. A stereophonic amplifier having "right" and "left" channels, respective "right" and "left" high-frequency speakers and a common low-frequency speaker, and frequency-selective output coupling means between said stereo channels and said speakers effective to maintain stereo separation of the high-frequency signals and to combine the low-frequency signals of the two channels, said coupling means including a transformer having "right" and "left" primary windings, "right" and "left" secondary windings each coupled tightly to a respective one of said primary windings, an additional secondary winding, a magnetic core providing a common loop linking said windings, said windings being spaced apart and said primary windings being symmetrically disposed with respect to said additional winding to insure loose coupling between each primary winding and said additional winding, the winding sense of said primary windings in relation to said additional secondary winding being such as to induce aiding voltages in said additional winding in response to oppositely phased signals in the output of said channels, said additional winding being connected to each of said secondary windings in series-opposition and each pair of series-opposed windings providing a pair of terminals for a respective high-frequency speaker, a capacitor connected across said additional winding and relatively proportioned to determine the cross-over frequency, and a common low-frequency speaker connected to said additional secondary winding.

5. A stereophonic amplifier having "right" and "left" channels, respective "right" and "left" high-frequency speakers and a common low-frequency speaker, and frequency-selective output coupling means between said stereo channels and said speakers effective to maintain stereo separation of the high-frequency signals and to combine the low-frequency signals of the two channels, said coupling means including a transformer having "right" and "left" primary windings, "right" and "left" secondary windings each coupled tightly to a respective one of said primary windings, an additional secondary winding, a rectangular magnetic core providing a common loop linking said windings, said primary windings being disposed on opposite sides of said rectangular core and said additional winding being disposed on an end of said rectangular core symmetrically between said primary windings to insure loose coupling between each primary winding and said additional winding, the winding sense of said primary windings in relation to said additional secondary winding being such as to induce aiding voltages in said additional winding in response to oppositely phased signals in the output of said channels, said additional winding being connected to each of said secondary windings in series-opposition and each connected pair of said series-opposed windings providing a pair of terminals for a respective high-frequency speaker, a capacitor connected across said additional winding and relatively proportioned to determine the cross-over frequency, and a common low-frequency speaker connected to said additional secondary winding.

6. A stereophonic amplifier having "right" and "left" channels, respective "right" and "left" high-frequency speakers and a common low-frequency speaker, and frequency-selective output coupling means between said stereo channels and said speakers effective to maintain stereo separation of the high-frequency signals and to combine the low-frequency signals of the two channels,

said coupling means including a transformer having a rectangular magnetic core, "right" and "left" windings on opposite legs of said core, a bifilar winding on one end of said rectangular core symmetrically spaced from said "right" and "left" windings, the halves of said bifilar winding having a joint where the start of one half is joined to the finish of the other half, said "right" winding being connected in series-opposition to one half of said bifilar winding at said joint and the opposite terminal of said one half of said bifilar winding and the opposite terminal of said "right" winding being connected to said "right" high-frequency speaker, the other half of said bifilar winding being likewise connected in series-opposition to said "left" winding and to said "left" speaker, a capacitor connected across said bifilar winding for determining the cross-over frequency, and a common low-frequency speaker connected to said bifilar winding.

7. A stereophonic amplifier in accordance with claim 6, wherein symmetrical negative feed-back loops are included between said windings and said channels, and wherein said joint between said bifilar winding halves is connected to said channels as a signal reference point.

8. Frequency-selective output coupling means for coupling two stereo channels to a pair of high-frequency speakers and a common low-frequency speaker and effective to maintain stereo separation of the high-frequency signals and to combine the low-frequency signals of the two channels, said coupling means including a transformer having "right" and "left" primary winding, "right" and "left" secondary windings each coupled tightly to a respective one of said primary windings, an additional secondary winding, a magnetic core providing a common loop linking said windings, said windings being spaced apart and said primary windings being symmetrically disposed with respect to said additional winding to insure loose coupling between each primary winding and said additional winding, said primary windings being connected to each other at a common direct-current energizing point and having respective terminals remote therefrom for said stereo channels, respectively, the winding sense of said primary windings in relation to said additional secondary winding being such as to induce aiding voltages in said additional winding in response to oppositely phased signals at said remote terminals, said additional winding being connected to each of said secondary windings in series-opposition and each connected pair of said series-opposed windings providing a pair of terminals for a respective high-frequency speaker, a capacitor connected across said additional winding and relatively proportioned to determine the cross-over frequency, and said additional secondary winding having terminals for connection to a common low-frequency speaker.

9. Output coupling means for a pair of stereo amplifying channels, including a transformer having a rectangular magnetic core and plural windings thereon, said core having opposite sides and opposite ends, said windings including a primary winding and a secondary winding tightly coupled thereto on each of said opposite sides and an additional winding on one of said core ends, said primary windings being connected to each other to provide a common direct-current energizing terminal and having a relative winding sense to induce aiding voltages in said additional winding when push-pull primary signals are provided, each of said secondary windings being connected in series-opposition to said additional winding for providing respective pairs of high-frequency stereo output terminals, and a capacitor connected across said additional winding and relatively proportioned to determine the cross-over frequency, said additional winding having terminals for a common low-frequency speaker for both stereo channels.

10. Output coupling means for a pair of stereo amplifying channels, including a transformer having a rectangular magnetic core and plural windings thereon, said core having opposite sides and opposite ends and said windings

including a stereo output winding on each of said core sides and a bifilar winding on one of said core ends, said bifilar winding having the start of one half connected at a common terminal to the finish of the other half, the stereo output windings also being connected to said terminal and said bifilar winding halves thus connected to said stereo output windings forming two output circuits in each of which a stereo winding and a bifilar half-winding are in series-opposition, the number of turns in the bifilar winding halves being equal to the number of turns in each stereo output winding, and a cross-over-frequency determining capacitor connected across said bifilar winding.

11. An output transformer for a pair of stereo amplifying channels, including a rectangular core comprising U-shaped laminations of unequal-length legs and I-shaped laminations complementary to said U-shaped laminations and stacked in reversed alternation to form said rectangular core, said transformer including duplicate stereo signal windings on said core legs, respectively, and a common winding on said I-shaped laminations symmetrically disposed relative to said stereo signal windings, and said stereo windings being individually connected to said common winding in series-opposed relation.

12. An output transformer for a pair of stereo channels, including a rectangular core comprising U-shaped laminations of unequal-length legs and I-shaped laminations complementary to said U-shaped laminations and stacked in reversed alternation to form said rectangular core, said transformer including duplicate stereo signal windings on said core legs, respectively, and a bifilar winding on said I-shaped laminations, each half of said bifilar winding being equal in number of turns to one of said stereo windings and connected to a respective one of said stereo windings in series-opposition, the start of one of the bifilar winding halves being joined to the finish of the other.

13. An output transformer for a pair of stereo amplifying channels, said transformer having a rectangular core comprising opposite sides and ends, a primary winding and secondary winding tightly coupled thereto on each of said core sides, a common bifilar winding on one of said core ends, said primary windings being connected to each other and having a relative winding sense such that push-pull signals to said primary windings will induce aiding voltages in said bifilar winding, the start of one half of the bifilar winding being connected to the finish of the other half of the bifilar winding and said secondary windings also being connected to each other at said connection between the bifilar winding halves, the winding sense of each secondary being opposite that of a respective one of said bifilar winding halves.

14. An output transformer for a pair of stereo channels, said transformer having a rectangular magnetic core and plural windings thereon, said core having opposite sides and opposite ends and said windings including a stereo output winding on each of said core sides and a bifilar winding on one of said core ends, said bifilar winding having the start of one half connected at a common terminal to the finish of the other half, the stereo output windings also being connected to said terminal and said bifilar winding halves thus connected to said stereo output windings forming two output circuits in each of which a stereo winding and a bifilar half-winding are in series-opposition, the number of turns in the bifilar winding halves being equal to the number of turns in each stereo output winding.

15. A stereophonic amplifier, including "right" and "left" amplifying channels and a common output transformer, said transformer having a closed-loop core of magnetic laminations, a number of windings on said core including a common winding, and a pair of additional windings each having an output terminal and a ter-

5 minal connected to a respective terminal of said common winding, and each said additional winding being series-opposed relative to said common winding and symmetrically spaced therefrom so as to produce leakage reactance between said common winding and each of said additional windings, a condenser connected across said common winding and relatively proportioned to establish a cross-over frequency, and a pair of stereo speakers connected to said additional windings, respectively.

10 16. A stereo amplifier in accordance with claim 15, including separate high-frequency and low-frequency adjustable negative feedback paths from the output of said transformer to each of said stereo amplifying channels, 15 said low-frequency negative feedback paths having their input connections at the terminals of said common winding.

17. A stereophonic amplifier including "right" and "left" amplifying channels and a common output transformer for both of said channels, said transformer having a closed-loop magnetic core, a bifilar winding on said core, said bifilar winding having the start of one half thereof connected at a common terminal to the finish of the other half thereof, a pair of additional windings 25 on said core remote from each other and symmetrically disposed with respect to said bifilar winding, said bifilar winding and said additional windings having a substantial leakage reactance therebetween, each of said additional windings being connected to a respective amplifying channel and to a terminal of a respective half of said bifilar winding in series-opposition thereto, a capacitor connected across the bifilar winding relatively proportioned to establish a cross-over frequency between low-frequencies and high-frequencies, and respective low-frequency adjustable negative-feedback signal paths between the terminals of said bifilar winding and said stereo channels, each of said stereo channels also having a reference connection to said common terminal of said bifilar winding.

40 18. A stereophonic amplifier in accordance with claim 17, additionally including a pair of high-frequency selective adjustable negative feedback paths connected from said additional windings to said amplifying channels, respectively.

45 19. A stereophonic amplifier including "right" and "left" amplifying channels and a common output transformer, said transformer having a closed-loop core of magnetic material, three windings on said core including a common winding and an additional pair of windings on said core symmetrically disposed relative to said common winding and arranged to have leakage reactance between said common winding and each of said additional windings, a condenser connected across said common winding and relatively proportioned to establish a cross-over frequency, coupling means for applying output from each of said channels to a respective one of said additional windings, and a pair of full-range dynamic speakers, each speaker being connected to a respective one of said additional windings and to said common winding, the windings connected to each speaker being series-aiding, and each speaker having a rising impedance characteristic below said cross-over frequency and said common winding having a number of turns greatly in excess of each said additional winding.

55 20. A stereophonic amplifier in accordance with claim 19, wherein said common winding has a center-tap that is connected said amplifying channels as a signal reference point and wherein a pair of adjustable negative-feedback bass gain control circuits are connected between the respective terminals of said common winding and the amplifying channels, respectively.
